(57) **CLAIM**

The ornamental design for a protective sleeve for golf tees, as shown and described.

DESCRIPTION

FIG. 1 is a perspective view of a protective sleeve showing my new design;

FIG. 2 is a front elevational view thereof, the broken line showing of the golf ball and bottom portion of the tee is included for the purpose of illustrating and forms no part of the claimed design;

FIG. 3 is a left side elevational view of FIG. 1;

FIG. 4 is a right side elevational view of FIG. 1;

FIG. 5 is a rear elevational view of FIG. 1;

FIG. 6 is a top plan view of FIG. 1; and,

FIG. 7 is a bottom plan view of FIG. 1.
